J. F. WHITNEY.

BACK AND HANDLE FOR BRUSHES.

No. 20,345.

Patented Nov. 18, 1890.

UNITED STATES PATENT OFFICE.

JOHN F. WHITNEY, OF BROOKLYN, ASSIGNOR TO DOMINICK & HAFF, OF NEW YORK, N. Y.

DESIGN FOR A BACK AND HANDLE FOR BRUSHES.

SPECIFICATION forming part of Design No. 20,345, dated November 18, 1890.

Application filed July 30, 1890. Serial No. 360,396. Term of patent 7 years.

To all whom it may concern:
Be it known that I, JOHN F. WHITNEY, of the city of Brooklyn, in the county of Kings and State of New York, have invented and 5 produced a new, original, and useful Design for Backs of Brushes, Mirrors, and other Toilet Articles, of which the following is a description, reference being made to the accompanying photograph, which fully illustrates the 10 design.

The leading feature of the design is a bouquet composed of a central straight stalk and side festoon-like branches of flowers and leaves.

15 In the accompanying photograph, A represents a triple bow-knot at the upper end of the body part of a hand-mirror or brush. This knot is made up of a ribbon. Its bows are shown floating and its ends streaming. 20 From this knot springs the central straight

stalk B, which is tipped with a cluster of flowers and leaves. From the sides of the central stalk are two festoon-like branches or springs C, which curve outwardly and carry flowers and leaves graduated in size from 25 stem to tip, as also the short curving branches or sprigs D, which are tipped with flowers and leaves similar in form and arrangement to those above described.

This design may be included within a double 30 border H, the outer bead of which bears the inturning stipules I.

What I claim is—

The design for backs of brushes, mirrors, and other toilet articles, substantially as 35 herein shown and described.

JOHN F. WHITNEY.

Witnesses:

JOHN CHATELLIER,
C. O. SCHUYLER.
